UNITED STATES PATENT OFFICE

JOHN L. COX AND BERNARD M. FINE, OF PHILADELPHIA, PENNSYLVANIA

PROJECTILE PROVIDED WITH WINDSHIELD

Application filed October 11, 1930. Serial No. 488,035.

This invention relates to a projectile provided with a windshield.

It has been customary to provide projectiles with windshields made of cast or forged metal for the purpose of minimizing wind resistance to the flight of the shell. It is desirable that windshields be removably secured to the projectiles proper. It is found desirable that the windshield be of very light construction, and a suitable type of windshield may be made of drawn steel. However, although it is easy to removably secure to a projectile a machined casting or forging, it is difficult to removably secure to a projectile 15 a drawn steel windshield due to the fact that the walls are relatively thin and of substantially uniform thickness.

In order to so secure to a projectile a windshield of drawn steel as to insure against dis- 20 placement of the windshield during handling of the projectile or during its flight, it is known (see Cox and Fine Patent No. 1,760, 685) to permanently secure to the rear end of the windshield a ring having an interior 25 thread engaging an exterior thread on the projectile and which abuts against a circumferential forwardly facing shoulder on the projectile.

Our present invention is a specific embodiment of the said Cox and Fine invention, but is an improvement thereover in that the rear end of the windshield proper, as well as the rear end of the permanently secured ring, abuts against the circumferentially forward- 35 ly facing shoulder on the projectile. It also has been found advantageous to further modify the prior construction by providing on the projectile a circumferential shoulder which extends from its periphery in a rear- 40 wardly inclined direction and by shaping the concentric end walls of windshield and ring to fit such shoulder so that in effect the outer edge of the shoulder will overhang the rear ends of the windshield and ring. It also has been found advantageous to have the ring 45 gradually increase in thickness from front to rear for purposes hereinafter explained.

In the drawings:

Fig. 1 is a sectional view showing the wind-

shield applied to the point of a capped shell (service projectile).

Fig. 2 is an enlarged detail of Fig. 1.

Fig. 3 is a view showing the windshield applied directly to the point of a shell body un- 55 provided with a cap (target projectile).

A projectile having a body *a* is provided with a cap *b* of any desired type, which may be secured to the body in any suitable way. A windshield *c* of drawn steel and having 60 relatively thin walls of substantially uniform thickness covers the forward portion of the cap and acts to reduce the resistance of the air to the flight of the projectile. Within the rear end of the windshield is secured, by 65 any suitable means, such as welding, soldering, riveting or the like, a metallic ring *d*. The rear end walls of the windshield and ring are flush, it being advisable, in order to insure this condition, to turn these walls off 70 after the ring is secured.

It is also preferred that these end walls shall extend, from the peripheral edge of the wind- 75 shield wall to the internal edge of the ring, in a rearwardly inclined direction. The cap *b* is reduced in diameter, at an appropriate distance in front of its rear end, in an amount equalling the combined thicknesses of wind- 80 shield and ring, the shoulder thus formed being preferably inclined inward to afford a self-locking seat for the ring and the rear end of the windshield. By reason of this equality of thickness, the peripheries of the rear end of the cap and of the abutting rear end of the windshield will be flush, thus pro- 85 viding a continuous outer smooth surface from the rear end of the cap to the point of the windshield.

The ring *d* and the cap *b* are provided with interengaging screw threads, as indicated at 90 *e*, whereby the windshield with its secured ring may be screwed as a unit onto and off the cap.

The forward direction of longitudinal ex- 95 tension of the windshield and ring is slightly convergent toward the axis of the shell. It is desirable, although not essential, to make the ring of a thickness which gradually increases from front to rear, so that the internal screw thread on the ring will be substantially paral- 100

lel with the axis of the shell, the external screw thread on the cap being, of course, also parallel with said axis.

Instead of securing the windshield to the 5 cap, it may be secured, through ring *d*, direct to the body of the shell, as shown in Fig. 3.

Ring *d* may be secured against rotation to prevent accidental displacement or removal of the windshield by any of the means set 10 forth in the said Cox and Fine patent.

Instead of making the windshield of drawn steel, it may be stamped and pressed; a practicable procedure being to form the windshield in longitudinal halves and then weld 15 the halves together. It should be understood that a windshield of this character is an equivalent of the drawn steel windshield claimed. It is distinctly preferred, however, to make the windshield of drawn steel.

20 Having now fully described our invention, what we claim and desire to protect by Letters Patent is:

1. A projectile having a circumferential 25 forwardly facing shoulder, in combination with a windshield of drawn steel whose rear end is of substantially no greater thickness than its main body, a ring permanently secured within the rear end of the windshield, and means for detachably attaching the ring 30 to the projectile, the rear end of the windshield as well as the rear end of the ring abutting against said shoulder.

2. A projectile comprising a body and a 35 cap covering the point of the body and having a forwardly facing shoulder, in combination with a windshield of drawn steel whose rear end is of substantially no greater thickness than its main body, a ring permanently secured within the rear end of the windshield, 40 and means for detachably attaching the ring to the cap, the rear end of the windshield as well as the rear end of the ring abutting against said shoulder.

3. A projectile having a circumferential 45 forwardly facing shoulder, in combination with a windshield of drawn steel whose rear end is of substantially no greater thickness than its main body, a ring permanently secured within the rear end of the windshield, 50 and means for detachably attaching the ring to the projectile, the rear concentric walls of windshield and base ring being flush one with the other, said rear walls and the forwardly facing shoulder sloping from their peripheries rearward toward the axis of the projectile.

4. A projectile having a circumferential 60 forwardly facing shoulder, in combination with a windshield of drawn steel whose rear end is of substantially no greater thickness than its main body, a ring permanently secured within the rear end of the windshield, 65 said ring increasing in thickness in a rearward direction and having an interior screw thread engaging an exterior screw thread on

the projectile, said threads extending in a surface substantially concentric with the axis of the projectile, the rear ends of both windshield and ring abutting against said shoulder.

5. A windshield for a projectile, comprising a body of comparatively thin material and a base ring having an internal screw thread and permanently secured within the rear end of the windshield, the rear concentric walls of windshield and base ring being flush one with the other to adapt them both to seat together against a shouldered projectile body or cap.

6. A windshield for a projectile, comprising a body of comparatively thin material and a base ring having an internal screw thread and permanently secured within the rear end of the windshield, the rear concentric walls of windshield and base ring being flush one with the other and sloping rearwardly from the outer rear peripheral edge of the windshield inward toward the axis of the projectile to adapt them to seat against a similarly sloping forwardly facing shoulder on a projectile body or cap.

7. A windshield for a projectile, comprising a body of comparatively thin material and a base ring having an internal screw thread and permanently secured within the rear end of the windshield, the windshield converging from its rear end toward its point and the ring increasing in thickness in a rearward direction, the said internal screw thread extending in a surface substantially concentric with the axis of the windshield.

In testimony of which invention, we have hereunto set our hands at Philadelphia, Pennsylvania, on this 19th day of September, 1930.
